UNITED STATES PATENT OFFICE.

VICTOR H. JENNINGS, OF WORCESTER, MASSACHUSETTS, ASSIGNOR, BY MESNE ASSIGNMENTS, TO MILLS WOVEN CARTRIDGE BELT COMPANY, OF WORCESTER, MASSACHUSETTS, A CORPORATION OF MASSACHUSETTS.

RECEPTACLE OR POCKET AND METHOD OF MAKING SAME.

1,338,776.

Specification of Letters Patent.

Patented May 4, 1920.

Application filed October 15, 1917. Serial No. 196,586.

To all whom it may concern:

Be it known that I, VICTOR H. JENNINGS, a citizen of the United States, residing at Worcester, in the county of Worcester, State 5 of Massachusetts, have invented a certain new and useful Improvement in Receptacles or Pockets and Methods of Making the Same, of which the following is a specification, reference being had therein to the accompanying drawings.

The invention comprises improvements in receptacles or pockets of woven material on the order of those which constitute elements of military equipment, or accessories. It 15 comprises, also, improvements in the method of making such receptacles or pockets.

The invention is applicable in the manufacture of receptacles or pockets employed as containers for cartridges and other purely 20 military material, first-aid supplies, and various other articles or materials, and which may be combined with, applied to, or hung from belts or other parts of a soldier's equipment, or hospital corps belts, 25 or used separately or conjointly in other ways.

The invention relates particularly to receptacles or pockets having partitions by which the interior of a receptacle or pocket 30 is divided into compartments, and to the manufacture of receptacles or pockets with partitions. It enables such receptacles or pockets to be manufactured by simpler procedure and loom mechanism in performing 35 the necessary weaving than heretofore in the case of partitioned pockets; also, to be manufactured more quickly; consequently at smaller cost than heretofore and with an increased rate of production. It provides, 40 also, for production of single receptacles or pockets free from external ends, projections, or fins. It provides, further, for the production of flat or satchel-bottomed "square" 45 partitioned receptacles or pockets.

Briefly stated, the improvements in receptacles or pockets include a receptacle or pocket having one or more partition-webs, integral at one end thereof with a wall of the receptacle or pocket and secured at the 50 other end thereof by applied fastenings. The latter end preferably, though not necessarily in all cases, is covered by a lip which is integral with the corresponding wall of

the receptacle or pocket. When two partition-webs are provided they may be and 55 preferably are spread away from each other by spaced-apart lines of fastenings at both ends of the receptacle or pocket. The upper edges of the partition-webs preferably are selvaged, and preferably the lower edges 60 also. The flat or satchel-bottom, and the squaring of the receptacle or pocket, preferably are produced by means of lines of applied fastenings crossing or subtending the lower corners of the woven pocket or receptacle. These various features may be combined in a receptacle or pocket, or one or more thereof may be utilized in some cases without the others. They preferably are embodied in a receptacle or pocket having 70 front and back walls, and bottom, woven integral with one another.

The improvements in the method of making receptacles or pockets comprise special procedure in weaving and subsequent thereto, as hereinafter described and claimed.

The accompanying drawings show illustrative embodiments of the improvements in receptacles or pockets, and also show successive steps of the new method of manufacturing receptacles or pockets.

In the drawings,—

Figure 1 is an isometric oblique view of a partitioned "square" and flat or satchel-bottomed receptacle or pocket which is one 85 of the said illustrative embodiments.

Figs. 2 and 3 are views in section in the planes indicated by lines 2, 2, and 3, 3, Fig. 1.

Figs. 4 and 5 are sectional detail views showing the opposite end-portions of the 90 lower part of the receptacle or pocket of Figs. 1, 2, and 3.

Fig. 6, Sheet 2, is an isometric oblique view of a short length of a pocket-web, as produced in a loom, portions being broken 95 out on account of want of space.

Fig. 7, Sheet 2, is a detail view showing the manner in which the two plies or webs of the partition-sections are connected at intervals along their lower edges by portions 100 of weft-thread extending from one to the other and vice versa.

Fig. 8, Sheet 3, is an isometric oblique view of a blank for a receptacle or pocket, produced by cutting up the web of Fig. 6 105 into lengths.

Fig. 9, Sheet 2, is an oblique view showing the line of fastenings which crosses or subtends one of the lower corners of a receptacle or pocket, with the latter flattened down 5 for the application of such line, as in the process of manufacture.

Fig. 10, Sheet 3, shows the blank of Fig. 8, after the body-portion has been squared by the formation of the corner-seams.

10 Fig. 11, Sheet 3, shows the two partition-webs turned around alongside the side-walls of the squared body-portion.

15 Fig. 12, Sheet 3, shows the receptacle or blank after the free ends of the partition-webs have been attached at the end of the body-portion opposite that end of the latter from which such webs spring.

20 Figs. 13 and 14, Sheet 4, show receptacles or pockets having a single partition.

25 The flat or satchel-bottomed "square" receptacle or pocket of Figs. 1 to 5 embodies in one construction the various improvements in receptacles or pockets which are comprised in the present invention. It is produced in conformity with the improvements aforesaid in the method of making receptacles or pockets. It has opposite side-walls 1, 1, end-walls 2, 2^a, a flat bottom 3, and two partitions 4, 4; (a pair) above said 30 flat bottom, extending from one end-wall to the other. The two partition-webs are integrally united at one end, at 2^b, with the middle of the width of the end-wall 2. They extend away from each other in opposite directions at the face of said end-wall, the proper extent of separation of the two partitions being maintained by vertical lines of fastenings, 5, 5, engaging with the partition-webs and with the said end-wall, the said 35 vertical lines being spaced apart transversely of the receptacle or pocket at a distance corresponding to the said extent of separation. The free ends of the partition-webs are in contact with the opposite end-wall, 2^a, and are covered by covering lips 6, 6, which latter are integral with said end-wall 2^a and extend outward in opposite directions from a vertical line of union, 2^c, therewith. At this end of the receptacle or pocket the 40 required extent of separation of the two partitions is maintained by vertical lines of fastenings 7, 7, engaging with the covering-lips, partition-webs, and end-wall, and spaced at the proper distance apart transversely of the receptacle or pocket. Additional lines of fastenings 8, 8, are applied horizontally at the upper and lower ends of the lines 5, 5, and 7, 7. The lower ends of 45 the end-walls 2, 2^a, and the opposite ends of 50 the bottom 3 are fastened together at the respective ends of the receptacle or pocket by straight cross-lines 10, 10, of fastenings defining the angles between the end-walls and the bottom and producing the square shape 55 of the receptacle or pocket in horizontal

cross-section and the flat or satchel bottom. The continuations of the end-walls and bottom beyond the lines 10, 10, of fastenings constitute triangular lugs or ears 9, 9, which are inturned and underlie the lower edges 70 of the partitions 4, 4. The various lines of fastenings preferably are stitches, forming stitched seams.

The method of making the receptacle or pocket of Figs. 1 to 5 is as follows:

75 A pocket-web on the order of that shown in Fig. 6, Sheet 2, is woven. Such web comprises alternate body-sections *a* and partition-sections *b*. The said figure, for want of space, shows only one body-section and one 80 partition-section, both partly broken away, and connected portions of the adjoining body-section and partition-section. This web is composed of two cloths, *x*, *x*, woven face to face, which are separate from each 85 other except at the transverse lines of union 2^b, 2^c, defining the closed ends of the body-sections, and also along one margin of the web, namely the lower margin in Fig. 6. The two cloths *x*, *x*, have distinct selvages 90 along the other margin of the web, namely the upper margin in Fig. 6, which is at the top in the completed receptacle or pocket. At the lower margin of the web in Fig. 6, the two cloths are solidly united throughout 95 the length of a body-section *a* to close the bottom of the latter, and also for short distances beyond the lines 2^b, 2^c, of transverse union, by the weft-thread crossing from one cloth to the other, and vice versa, after every 100 pick that extends toward such margin in either cloth, as well-known to weavers. Along the partition-sections the weft-thread may be similarly crossed over from one cloth to the other and vice versa, but preferably 105 the crossing-over occurs after a greater number of picks in either cloth, as four for instance, as indicated at *v*, *v*, in Fig. 7. Thereby practically distinct selvages are formed at the lower margin of each partition-section, with such selvages connected together at intervals by the weft-thread passing over from one to the other thereof, and vice versa, as in said figure. The partition-sections are narrower than the body-sections, the warp-threads *w* which are interwoven in the lower portions of the body-sections but not in those of the partition-sections being floated from one body-section 110 to the next, as in Fig. 6. The body-sections 115 are made wider than the partition-sections in order to provide the necessary width of material for the flat or square pocket-bottoms.

120 The pocket-web of Fig. 6 is cut up into blanks corresponding with that shown in Fig. 8, by being severed on lines *a*, *a*, Fig. 6, across the partition-sections near the transverse lines 2^b, 2^c, of union of the two cloths *x*, *x*. Each blank comprises a body-section 125

a, with partition-webs 4, 4, projecting from one end thereof, and short lips 6, 6, projecting from the other end thereof. The floated warps are trimmed off.

5 The squaring of the receptacle or pocket and its bottom is effected by flattening each lower corner of the body-portion thereof in turn as in Fig. 9, Sheet 2, and applying a line of fastenings 10 so as to cross or sub-
10 tend the flattened corner. The stage in the manufacture reached thereby is illus-
trated in Fig. 10. By this squaring of the receptacle or pocket the end-portions of
15 the two webs constituting the opposite sides of the body-portion are caused to stand at right-angles to the intermediate portions of such webs, thereby constituting the end-walls 2, 2^a, and the lower part of the body-portion also is flattened out transversely so
20 as to produce the flat or satchel-bottom.

The bottom margins of the partition-webs 4^b, 4^b, are separated from each other by cutting. When the said margins are united as in Fig. 7 in weaving the pocket-web, the
25 cutting of the connecting portions *v*, *v*, of weft-thread leaves the partition-webs furnished with practically perfect selvages, which are preferred rather than raw edges.

After the disconnection of the bottom
30 margins of the partition-webs from each other, the partition-webs are bent in opposite directions as in Fig. 11, Sheet 3, around the body-portion, and their free ends are attached to the opposite end of the body-
35 portion, as in Fig. 12, Sheet 3. For the attachment the narrow projecting portions 6, 6, are turned in opposite directions away from each other, producing thereby the lips of Fig. 12 and Figs. 1 to 5, and the said free ends of the partition-webs are inserted
40 between such lips and the exterior of the said end of the body-portion, and the vertical lines of fastenings 7, 7, are engaged with the three thicknesses. The horizontal lines
45 8, 8, of fastenings are then applied. At the other end of the body-portion the vertical lines 5, 5, of fastenings, and horizontal lines 8, 8, are applied.

The receptacle or pocket having been
50 brought to its condition in Fig. 12, is turned inside out as in Fig. 1. This operation places the partition-webs 4, 4, inside the pocket, where they constitute the partitions, and in addition places the lugs or ears 9, 9, inside the receptacle or pocket, under the lower edges of the partitions 4, 4.

If a single partition is desired, the two partition-webs may be fastened together, with their proximate faces contacting, as at
55 4^b, 4^b, in Fig. 13, Sheet 4, in which case the free ends of the combined partition-webs may be inclosed between the two lips 6, 6, and secured by fastenings 11, preferably stitches. Or the partition-section of the
60 blank for a receptacle or pocket may com-

prise a single cloth, as 4^c, Fig. 14, Sheet 4, the free end of which may be lapped with a single lip 6^c projecting from the body-portion and be fastened to the said lip, as by a line of fastenings 12. The relative lengths 70 of the elements 4^c and 6^c of the partition may vary in practice.

Briefly summarized, the most characteristic steps of the herein-described novel and improved method of making partitioned woven receptacles or pockets consist in weaving a pocket-web comprising opposed walls joined together in the weaving so as to close the ends of the receptacle or pocket, weaving a continuation of the pocket-web 80 beyond one of the places where the walls are joined together, or a pair of such continuations face to face, then bending such continuation around outside the body-portion of the receptacle or pocket, or in the case 85 of the pair of continuations bending the latter in opposite directions around such body-portion, attaching the free end or ends to the opposite end of the body-portion, and turning the receptacle or pocket inside 90 out and thereby placing the partition or partitions inside the receptacle or pocket. In the case of the receptacles or pockets of Figs. 1 to 5, 13 and 14, these steps are accom-
95 panied by the operations by which the receptacle or pocket is made square and flat or satchel-bottomed, but the said steps may be practised without the addition of such operations, as for the production of receptacles or pockets which are not square or 100 flat-bottomed. When it is found necessary, the partition-web or webs may have a greater relative width than in the drawings, in order that the lower edge or edges thereof may be brought as close as desired to the 105 bottom of the receptacle or pocket.

In some cases, the lugs or ears 9, 9, may be cut away alongside the lines of fastenings 10, 10.

The bottom of the receptacle or pocket 110 may be reinforced in the weaving in any of the ways known in the art.

Receptacles or pockets made in accordance with the invention will be furnished in practice, as may be required, with covers or 115 flaps of approved character, not necessary to be shown herein.

If preferred, the two web-continuations 4, 4, constituting the partition-section may be woven with their lower edges entirely un-
120 connected with each other, by well-known processes of weaving, thereby obviating all necessity for cutting such edges apart, as well as furnishing them with finished selvages.

What is claimed as the invention is:—

1. A receptacle or pocket having front back and end walls, and bottom, woven integral with one another, and also having a partition which is interwoven at one end 130

thereof with one wall and secured at the other end thereof to the opposite wall by applied fastenings.

2. A receptacle or pocket having front back and end walls, and bottom, woven integral with one another, and also having a pair of partitions which are interwoven at one end thereof with one wall and secured at the other end thereof to the opposite wall 70 by applied fastenings.

3. A receptacle or pocket having front back and end walls, and bottom, woven integral with one another, and also having a pair of partitions which are interwoven at 15 one end thereof with one wall, spread away from each other by spaced-apart lines of applied fastenings engaging with the said wall, and secured at the other end thereof to the opposite wall by spaced-apart lines 20 of applied fastenings.

4. A satchel-bottomed receptacle or pocket having front back and end walls, and bottom, woven integral with one another, and also having above its flat bottom a partition 25 which is interwoven at one end thereof with one wall and secured at the other end thereof to the opposite wall by applied fastenings.

5. A satchel-bottomed receptacle or pocket 30 having front back and end walls, and bottom, woven integral with one another, and also having above its flat bottom a pair of partitions which are interwoven at one end thereof with one wall and secured at the 35 other end thereof to the opposite wall by applied fastenings.

6. A satchel-bottomed receptacle or pocket 40 having front back and end walls, and bottom, woven integral with one another, and also having above its flat bottom a pair of partitions which are interwoven at one end thereof with one wall, spread away from each other by spaced-apart lines of applied fastenings engaging with the said wall, and 45 secured at the other end thereof to the opposite wall by spaced-apart lines of applied fastenings.

7. A receptacle or pocket of woven material having a partition-web which is integral 50 at one end thereof with a wall of the receptacle or pocket and secured at the other end thereof by applied fastenings beneath a covering lip which is integral with a wall.

8. A receptacle or pocket of woven material 55 having a pair of partition-webs which are integral at one end thereof with a wall of the receptacle or pocket and secured at their other ends by applied fastenings beneath covering lips which are integral with a wall.

9. A receptacle or pocket of woven material 60 having a pair of partition-webs which are integral at one end thereof with a wall of the receptacle or pocket, spread apart from each other by spaced-apart lines of

applied fastenings engaging with the said wall, and secured at the other end thereof by spaced-apart applied fastenings beneath covering lips which are integral with a wall.

10. A woven receptacle or pocket closed 70 at its ends by the weaving together of opposite walls thereof, and having a transverse partition formed of a woven continuation of the pocket-web beyond the place at which the said walls are woven together. 75

11. A woven receptacle or pocket closed at its ends by the weaving together of opposite walls thereof, and having a plurality of partitions formed of woven continuations of the pocket-web beyond the place at which 80 the said walls are woven together.

12. The method of making a partitioned woven receptacle or pocket consisting in weaving a pocket-web comprising opposed walls joined together in the weaving to close 85 the ends of the body-portion of the receptacle or pocket, weaving a continuation of the pocket-web beyond one of the places where the walls are joined together, then bending such continuation around outside 90 the body-portion of the receptacle or pocket and attaching it to the opposite end of the said body-portion, and turning the receptacle or pocket inside out and thereby placing the partition within the receptacle or 95 pocket.

13. The method of making a partitioned woven receptacle or pocket consisting in weaving a pocket-web comprising opposed walls joined in the weaving to close the ends 100 of the body-portion of the receptacle or pocket, weaving a pair of continuations of the pocket-web face to face beyond one of the places where the walls are joined together, then bending such continuations in 105 opposite directions around the body-portion of the receptacle or pocket and attaching their free ends to the opposite end of the said body-portion, and turning the receptacle or pocket inside out so as to place the 110 partitions within the receptacle or pocket.

14. The method of making a partitioned satchel-bottomed woven receptacle or pocket which consists in weaving a pocket-web comprising opposed walls joined together in the 115 weaving to close the ends and bottom of the body-portion of receptacle or pocket, weaving a narrower continuation of the pocket-web beyond one of the closed ends to constitute a partition-piece, bending such continuation or partition-piece around outside one wall of the body-portion of the receptacle or pocket and attaching it to the opposite end of the said body-portion, squaring the bottom by lines of applied fastenings 120 subtending the lower corners of the pocket-web below the partition-piece, and turning the receptacle or pocket inside out and thereby placing the partition within the receptacle or pocket. 125

15. The method of making a partitioned satchel-bottomed woven receptacle or pocket which consists in weaving a pocket-web comprising opposed walls joined together in the weaving to close the ends and bottom of the body-portion of the receptacle or pocket, weaving a pair of narrower continuations of the pocket-web beyond one of the closed ends to constitute partition-pieces, bending such continuations or partition-pieces in opposite directions around outside the body-portion of the receptacle or pocket and attaching them to the opposite end of the said body-portion, squaring the bottom by lines of applied fastenings subtending the lower corners of the pocket-web below the partition-pieces, and then turning the receptacle or pocket inside out and thereby placing the partition within the receptacle or pocket.
16. A receptacle or pocket of woven material having seamless end-walls and also having a partition-web which is integral at one end thereof with one of said end-walls and secured to the other end-wall by applied fastenings.
17. A receptacle or pocket of woven material having seamless end-walls and a pair of partition-webs with a receiving compartment between them, said partition-webs integral at one end thereof with one of said end-walls, and secured to the other end-wall by applied fastenings.

In testimony whereof I affix my signature in presence of two witnesses.

VICTOR H. JENNINGS.
